CLAIM

The ornamental design for a safety spotter support for barbells, as shown and described.

DESCRIPTION

FIG. 1 is a perspective view of a safety spotter support for barbells showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof, and

FIG. 7 is a bottom plan view thereof.
